HINGE

Axel W. Ahlgren, Rockford, Ill., assignor to Amerock Corporation, Rockford, Ill., a corporation of Illinois
Filed Apr. 15, 1960, Ser. No. 22,636
1 Claim. (Cl. 16—168)

This invention relates to a hinge for use in supporting a door on a frame to swing about a fixed axis between an opened and closed position. More particularly, the invention relates to butt type hinges having two leaves which include door and frame mounting portions projecting inwardly from the plane of the door to lie along the edges of the door and the frame and knuckle portions disposed outwardly of the plane of the door and joined together by a pivot pin, the door when mounted being flush with the frame.

The primary object of the invention is to provide a hinge of the above character having a pivot pin constructed in a novel manner so as to prevent the hanging of articles such as clothes, aprons and the like on the head of the pin.

A more detailed object is to shape the head so as to present a smooth outward contour and, at the same time, to project inwardly between the door and the frame to prevent articles from passing behind the head.

Other objects and advantages of the invention will become apparent from the following detailed description taken in connection with the accompanying drawings, in which

FIGURE 1 is a fragmentary perspective view of a door supported on a frame by a hinge embodying the novel features of the present invention.

FIG. 2 is a plan view of the hinge.

FIG. 3 is a sectional view taken along line 3—3 in FIG. 2.

FIG. 4 is a perspective view of a hinge pin.

FIG. 5 is a perspective view of a bearing.

For purposes of illustration, the present invention is shown in the drawings embodied in a hinge 10 for use in mounting a door 11 on a frame 12 to turn about a vertical axis between an open and closed position. The illustrated hinge 10 is of a type commonly known as a butt hinge and is utilized to mount a flush type door, that is, a door which, when closed, lies in the same plane as the frame. Such hinges include two leaves or wings, a frame leaf 13 and a door leaf 14, both of which extend inwardly between the edges of the door 11 and the frame 12 and which are pinned together to turn relative to each other about a vertical axis.

The leaves 13 and 14 include flat portions 15 which lie along the edge of the door 11 and of the frame 12 respectively and are secured to these members as by screws 16. In order to join the leaves 13 and 14 together, interfitting knuckles 17 and 18 are formed on one edge of the flat portions 15, the door leaf having a single knuckle 18 located between and in line with a pair of spaced knuckles 17 on the frame leaf (FIG. 3). The hinge is mounted by inserting the flat portions 15 between the edges of the door 11 and the frame 12 with the outer periphery of the knuckles 17 and 18 adjacent the outer face of the door and the frame. When the hinge 10 is used with a door and frame of hollow, box-like sheet metal construction as illustrated on the drawings, the flat portions 15 project through slots 19 formed in the face of the door and of the frame and extend along the inner side of the edge of the door and of the frame. The screws 16 are countersunk and extend through the edges and are threaded into the flat portions 15.

The two leaves 13 and 14 are joined together by a pivot pin 20 which is received in a bore 21 extending through the knuckles 17 and 18 and which has a head

2

22 on one end to abut the outer end of the knuckle 17. Herein, two such pins 20 are utilized, one inserted in each end of the bore 21. To reduce friction and wear, the surfaces of the leaves 13 and 14 which rub together as the door is swung open or closed are separated by bearings 23. These bearings 23 comprise cylindrical inserts of a suitable bearing material such as nylon and are adapted to be received in the bore 21 in the knuckle 18 on the door leaf 14. A radial flange 24 integral with one end of the bearing extends across the end of the knuckle 18 to separate it from the spaced knuckles 17 on the frame leaf. Two such inserts are used, one inserted in each end of the bore 21 in the knuckle 18 and each having an inside diameter adapted to receive the pivot pin 20.

A problem with the type hinge described above encountered especially in institutions such as dormitories, schools, hospitals and the like is that the headed pins of the hinges become catchalls on which various articles such as clothes and aprons are hung. The present invention contemplates a novel construction of the hinge pins 20 which results in a smooth outer contour presenting surface which is unable to support such articles. To this end, the head 22 of the pin 20 is curved toward the plane of the door 11 and a portion of the head extends into the crack between the door and the frame 12 to prevent hooking articles behind the head.

In the present instance, the head 22 of the pin 20 has a shoulder 25 adapted to abut the end of the knuckle 17 and having an outer diameter equal to the outer diameter of the knuckle. The head 22 is inclined inwardly away from the outer periphery of the shoulder 25 and convexly curved toward the plane of the door 11 in a somewhat bullet-like shape and terminates in a straight side parallel to the plane of the door and generally in line with the outer periphery of the knuckles 17 and 18. Thus, in cross section, the head 22 is substantially in the form of a quarter circle having two straight sides perpendicular to each other and joined by a curved side. One of the straight sides lies in a vertical plane coincident with the plane of the frame and the other lies in a horizontal plane defined by the end of the knuckle 17.

To prevent the hanging of articles on the hinge by hooking a portion of them behind the head 22 between the face of the door and frame and the head, a ridge 26 is formed along the vertical straight side of the head to extend laterally therefrom in the same direction and parallel to the flat portion 15 on the frame leaf 13. The ridge 26 projects inwardly beyond the face of the frame 12 and into the crack between the door 11 and the frame.

In order to maintain the pin 20 in the desired position as the door 11 is opened and closed, means formed on the shank of the pin prevents relative turning between the latter and the knuckle 17 formed on the frame leaf 13. Herein, this means comprises an enlarged serrated portion 27 integral with the pin 20 and having an outside diameter slightly larger than the inside diameter of the knuckle 17. The serrated portion 27 extends part way through the knuckle 17 when the pin 20 is inserted in the hinge. As the serrated portion 27 is forced into the bore 21 in the knuckle 17, the serrations bite into the bore and thus resist turning of the pin relative to the bore.

While only the top pin need be formed as described to accomplish the objects of the invention, preferably, the lower pin is also so formed. This preserves a symmetrical design and enhances the over-all appearance of the hinge.

It will be apparent that by the use of a hinge constructed as described above the unsightliness of having articles of clothing draped over the hinges on a door can be eliminated. At the same time, the hinge presents a pleasing appearance in that the heads of the pins at

either end are gracefully curved from the knuckles into the plane of the door.

I claim as my invention:

A hinge for hanging a door on a frame, said hinge having, in combination, a first leaf member having a flat portion adapted to lie against the frame and an integral knuckle portion formed along a vertical edge of the flat portion, a second leaf member having a flat portion adapted to lie against the door and an integral knuckle portion extending along a vertical edge of the flat portion and interleaved with the knuckle portion on said first leaf member, said two knuckle members having aligned vertical holes, a pin projecting into said holes to join said leaf members and having a head abutting against the upper end of one of said knuckles, said head having a vertical side disposed substantially in the plane of the

adjacent vertical edges of said flat portions, and a vertical ridge projecting laterally from said side and in between said leaf member, said ridge projecting beyond the adjacent vertical edges of said flat portions and said head being inclined and continuously curved convexly from the upper end of said ridge outwardly and downwardly to the bottom of the head.
